HOOK FORMING MACHINE

Ed Laxo, Oakland, Calif.

Application March 2, 1951, Serial No. 213,581

1 Claim. (Cl. 153—11)

This invention relates to a hook forming machine for forming hooks on can body blanks.

In forming hooks on can body blanks, i. e., hooks which are employed to form the side seams of can bodies, it is essential that the hooks be formed accurately and at a high speed. Accuracy is essential because, otherwise, faulty side seams will result. High speed is essential because of competitive conditions prevailing in the can industry.

It is an object of the present invention to provide an improved hook forming machine for forming hooks on can body blanks.

Yet another object of the invention is to provide a machine capable of forming hooks on can body blanks at a high speed.

Another object of the invention is to provide a machine capable of forming hooks on can body blanks with great accuracy and at high speed.

Still another object of the invention is to provide a hook forming machine of the character for the purpose described having a simplified construction.

Another object of the invention is to provide a hook forming machine of the character and for the purpose described which is easily adjustable.

Yet another object is to provide a hook forming machine of the character and for the purpose described which is easily timed, and in which the timing of the several elements of the machine with respect to each other, and of the machine as a whole with respect to other elements of a can body maker line, is facilitated by the provision of a common drive from a single crank-shaft.

Yet another object of the invention is to provide a machine having some or all of the advantageous features described herein and which is generally useful for the purpose of bending sheet metal objects and the like.

These and other objects of the invention will be apparent from the ensuing description and the appended claims.

One form of the invention is illustrated by way of example in the accompanying drawings and is described hereinafter.

Referring to the drawings:

Figure 1 is a view, partly in end elevation and partly in transverse section, of both the left and right-hand hook forming assemblies of a hook forming machine constructed in accordance with the invention.

Figure 2 is a fragmentary view similar to that of Figure 1 but on a larger scale and in which certain of the parts shown in Figure 1 are omitted. In Figure 2 the machine is shown at a different stage of operation than illustrated in Figure 1.

Figure 3 is similar to Figure 2, but illustrates the machine at a later stage in the operating cycle.

Figure 4 is a top view of the right-hand assembly of Figure 2.

2

Figure 5 is a side elevation as seen from the right of Figure 2.

Figure 6 is a section taken along the line 6—6 of Figure 2.

Figure 7 is a section taken along the lines 7—7 of Figure 2.

Referring now to the drawings, and more particularly to Figure 1, the machine as a whole is designated as 10 and it comprises more or less identical left- and right-hand assemblies which are designated as 11a and 11b, respectively. These assemblies are substantially identical and the ensuing description will be confined, for the most part, to the right-hand assembly 11b. Each assembly is mounted on frame members 12, the spacing of which may be adjusted by any suitable means (not shown) for can body blanks of different lengths.

The assemblies 11a and 11b have common drive in the form of a single crankshaft 13, which may also be employed to operate a notching machine in advance of the hook forming machine, and also to operate a can body maker for interlocking the hooks formed by the machine of Figure 1 and forming side seams therefrom. For example, the crankshaft 13 may be employed to operate the notching machine described and claimed in my co-pending application Serial No. 213,582, filed March 2, 1951, entitled "Notching Machine," now U. S. Patent No. 2,695,061, granted November 23, 1954, and the body maker described and claimed in my co-pending application Serial No. 165,617, filed June 2, 1950, entitled "Can Body Maker," now U. S. Patent No. 2,656,806, granted October 27, 1953.

As illustrated, the crankshaft 13 is provided with an eccentric 14 on which is rotatably mounted a split strap 14a whose parts are clamped together by means of cap screws 15. One half of the strap 14a is integral with one end of a connecting rod 16, the other end of which is rotatably connected at 16a to a rocker 17. The rocker 17 is rotatably mounted on a rocker shaft 18 which provides a fulcrum for the rocker. The right-hand end or arm of the rocker 17 is rotatably connected at 25 to the lower end of an adjustable connecting rod 26, the upper end of which is rotatably connected to a shaft 27. The left-hand end or arm of the rocker 17 is similarly connected to an adjustable connecting rod 26 which is similarly connected to a shaft 27.

Referring to Figures 1 and 2, it will be seen that can body blanks such as the blank shown at 28 are carried by a feed table 29 along which they are conveyed by any suitable means (not shown), such as reciprocating dogs. The blanks 28 are registered at the hook forming station by suitable registering means such as shown at 30. The registry means 30 are not shown in detail, and any of several known types of registry means may be used.

Referring to Figures 2 and 3, it will be seen that each body blank 28 protrudes beyond the edges of the feed table 29 and that the protruding edges are formed into hooks in two stages. First a right angular hook is formed as shown at 31 in Figure 2 and then a hook is formed which, as shown at 32 in Figure 3, forms an acute angle with the plane of the body blank. Preferably this angle is about 30°, but the precise angle may be varied.

The means for accomplishing this hook formation will now be described in detail. Referring more particularly to Figures 2 and 7, it will be seen that a U-shaped link 33 is provided having arms 34 which are rotatably mounted on the shaft 27, and that the link 33 is formed at its outer or right-hand end, as viewed in Figure 7, with a collar 35 which is rotatable on a shaft 36. The shaft 36 is fixed by means of set screws 37 to brackets 38 which are clamped, as by means of cap screws 45, to key mem-

bers 46 which are keyed at 47 to frame members 48. This arrangement allows the entire unit 11b to be shifted along the length of the frame, e. g., to adjust the spacing of the hook forming machine and other associated machines such as a notching machine and a body maker, for can body blanks of different widths.

As shown in Figures 1 and 2, one of the arms 34 of the U-shaped link 33 is formed with an upright bracket 49 which is formed with a slot 50. The slot 50 is best shown in Figure 7. A cam 51 is rotatable on the shaft 36 adjacent the bracket 49 and it is clamped to the bracket 49 by the means of a screw 52 extending through the slot 50 and a washer 53. It will be apparent that the cam 51 can be readily adjusted by loosening the screw 52, shifting the cam 51 and then tightening the screw 52 when suitable adjustment has been made.

The cam 51 is formed at its upper end with a low dwell 54, a rise 55 and a high dwell 56. It is in engagement with a roller 57 which is rotatable on an extension 58 of one branch or arm 59 of a U-shaped lever 60. The lever 60 is shown in elevation in Figure 2 and in top plan in Figure 4. The arms 59 of the lever 60 are rotatable on stub shafts 65 which are clamped to frame members 66 by cap screws 67. The inner or left-hand end of the lever 60, as viewed in Figure 2, is formed with a clamping head 68 which carries a yieldable clamping member 69 which is keyed into a recess 69a formed in the clamping head and is urged downwardly by an expansion spring 70. Also fixed to the clamping head and forming a part thereof is a forming die 71 having a lip 72. The lip 72 is formed at the angle to which it is desired to bend the can body hooks; for example, in the preferred embodiment, it is formed at an angle of 30°.

It will be apparent that, as the crankshaft 13 rotates and rocks the rocker 17, the cam 51 will oscillate about the axis of its shaft 36 and that the action thereof on the roller 57 will rock or oscillate the lever 60. It will, therefore, be apparent that the clamping head 68 will alternately descend, clamp a body blank 28 to the feed table 29 for the hook forming operation and then ascend to release the body blank for forward travel, e. g., to a can body maker. The yieldable clamping member 69 will clamp each body blank to the feed table prior to the end of the down stroke of the clamping head and will serve to hold the body blank in position during this interval of time.

The shaft 27 also rotatably carries arms 80 which are integral at their upper ends with a steel holder or head 81. A hook forming steel or die 82 having a plane, vertical face 82a is keyed into a dovetail recess 83 formed in the head 81 and it is formed with a lip 84 which is cooperable with the die 71 and whose face forms the same angle with the horizontal as the lip 72. The steel or die 82 is clamped to the head by means of a gib 85 and screws 86 (see Figure 4). During the initial part of its up stroke the lip 84 of the steel or die 82 bears against and is guided by a machined insert 86 fixed to the frame of the machine. The head 81 and the steel or die 82 are also guided for vertical movement from the position shown in Figure 1 to the position shown in Figure 2, that is, until the hook forming lips 72 and 84 are in the same horizontal plane, by guide means including a tension spring 88 which is connected at one end to a pin 89 fixed to the head 81 and at its other end to a pin 90 fixed to a bracket 91. The guide means also includes a roller 92 which is rotatably mounted on the bracket 91, and an adjustable cam 93 which is fixed to the head 81. The cam 93 is formed at its lower end with a rise 94 and along its upper portion with a vertical dwell 95. It will be apparent that the spring 88 will maintain the cam 93 in engagement with the roller 92 and that when the head 81 is located between the position shown in Figure 1 and that in Figure 2, the spring 88 and roller 92 will maintain the head in a vertical position. It will also be apparent that, as the head 81 moves upwardly from the position shown in Figure 2

to that shown in Figure 3 the action of the rise 94 against the roller 92 will rock the head 81, and with it the steel 82 and the lip 84 in counterclockwise direction as viewed in Figure 3. It will, therefore, be apparent that, during the initial stage of the up stroke of the head 81 and the steel or die 82, the latter will move vertically and will bend the protruding end of a can body blank at a right angle as shown in Figure 2. It will also be apparent that during the remainder of the upstroke, i. e., while moving from the position shown in Figure 2 to that shown in Figure 3, the steel or die 82 will be rocked to bend the right angle hook to a sharp angle.

The cam 93 is adjustable vertically by the means which will now be described in detail. Referring to Figures 2, 4 and 6, the cam 93 is keyed into a dovetail, longitudinal slot 96 formed in the head 81. A bracket 100 is fixed to the upper end of the cam 93 by a cap screw 101 and it is formed at its inner or left-hand, as viewed in Figure 2, with a U-shaped recess 102 to receive a shoulder screw 102a which is threaded into the head 81 as shown at 103 in Figure 2. It will be apparent that, by turning the screw 102a the cam 93 will be raised or lowered in its slot 96. When suitably adjusted, the cam 93 is clamped in adjusted position by means of a gib 104 and cap screws 105.

In operation, and referring only to the right-hand assembly 11b, as the crankshaft 13 rotates, the connecting rod 26 will reciprocate, thereby causing through the medium of the link 33, the cam 51 and the lever 60, the clamping head 68 to alternately clamp body blanks to the feed table and release them for forward movement to a body maker. Timing of this operation is readily accomplished by adjustment of the cam 51, i. e., by loosening the screw 52, shifting the cam 51 relatively to its supporting arm 49 and then tightening the screw 52. Simultaneously with the operation of the clamping head 68, the head 81 and with it the hook forming steel 82 are reciprocated to bend the protruding edge of a body blank, first to a right angle as shown in Figure 2 and then to an angle of 30° as shown in Figure 3 to form a finished hook. Timing of this operation is readily accomplished by loosening screws 105 in gib 104, turning the shoulder screw 102a and then tightening the screws 105 when suitable adjustment has been made. On the down stroke, of course, the spring 88 will return the head 81 to the vertical position shown in Figure 2.

The left-hand assembly 11a operates identically and has identical parts, which are similarly numbered. However, it will be seen that the hook is bent downwardly and the parts are, therefore, reversed.

Among the numerous advantages of the machine thus described may be mentioned the following:

The two parts of the assembly, that is to say, the right and left-hand assemblies 11a and 11b, are operated in precisely timed relation by means of a single crankshaft and a single rocker. Since this same crankshaft may be used for other elements of a can body maker line, such as a notching machine and a body maker, precise timing of a complete body maker line is facilitated, and the number of moving parts is greatly reduced.

Timing of the several elements of the machine, for example, of the can body clamping means and of the hook forming steel or die, is easily and speedily accomplished by the means described hereinabove. As a whole the machine of my invention is simple, is easily adjusted and it is easily repaired. Interchange or replacement of parts is easily and speedily accomplished. The machine is capable of high speed, dependable operation and it forms hooks with great accuracy. Slides are unnecessary for guiding the forming tools, which prevents galling and other difficulties inherent in slide structures.

I claim:

A can body hook forming machine comprising a stationary frame, a horizontal table fixed to said frame for supporting a can body blank thereon with an edge of the blank projecting beyond an edge of said table, a pair of

parallel generally horizontally disposed levers pivoted to said frame for oscillatory movement about a first horizontal axis parallel to said edge of said table, a pair of generally vertically disposed arms pivotally mounted at one end on free ends of said levers for pivotal movement about a second horizontal axis parallel to said edge of said table, a hook forming tool secured to the free ends of said arms, said tool having a flat vertical surface facing said edge of said table and arranged to engage the projecting edge of the body blank, said tool having a lip at one end of said flat vertical surface, a roller secured to said frame and rotatable about an axis parallel to said edge of said table, cam means fixed to said arms, spring means resiliently urging said cam means into engagement with said roller, said cam means having a vertical dwell portion causing said tool to partake of an increment of vertical movement upon oscillation of said levers, such increment of vertical movement causing said flat vertical surface of said tool to slide vertically relative to the projecting edge of the blank and subsequently causing said lip to engage and bend such projecting edge

to substantially a 90° angle to the blank, and said cam means having a rise portion causing said tool to rock toward said edge of said table after such 90° angle has been formed in the blank to thereby cause said lip to effect an acute angle fold in the blank.
